BY
Frank Head ^{ATTORNEY}

UNITED STATES PATENT OFFICE.

PHOEBE B. COOPER, OF BROOKLYN, NEW YORK.

DOLL.

Application filed August 8, 1925. Serial No. 48,921.

The objects of this invention are to provide a doll for infants, of a form adapted to be handled by small hands unaccustomed to grasping articles, which will be incapable of harming the child in any way, which will be of such a nature as not to be injured in the rough handling to which it will be subjected, which will possess sufficient novelty to hold the interest and which, further, will furnish incentive to helpful exercise.

These objects are attained in part by making the doll in a ring-like form of a cross sectional size such as to be readily grasped in the small fingers and of a size such as to receive the arm of the child, for carrying purposes, the head of the doll being provided by a substantially conical projection at one edge of the ring and the hands and feet being provided by appropriately positioned projections at the edges of the ring.

The details of the invention will appear as the specification proceeds.

In the drawing accompanying and forming part of this specification, one practical embodiment of the invention is illustrated in which:

Figure 1 is a side or face view of the doll, and

Figure 2 is a cross sectional view as on substantially the plane of line 2—2 of Figure 1.

The ring-like doll is formed with a central aperture 4 of a size to readily pass the hand and arm of a child, the aperture being surrounded by a perimetric body 3 of a cross sectional size to be readily grasped by childish hands.

At one edge, the upper edge in Figure 1, the ring is extended in a substantially conical projection 5, bearing the features of a face 6 and generally suggestive of a head.

At opposite sides of the head projection are the arm and hand projections 7 and below these at opposite sides of the same diametrical line are the foot projections 8.

These limb projections are only of sufficient extent to suggest the members indicated, being usually of less projection than the width of the ring so that they are practically a part of the ring and cannot be torn loose.

The doll may be moulded or otherwise

suitably shaped, of rubber or other material, preferably all in the one piece and be of a self-sustaining but relatively flexible nature so as to yield in the hands of the child. The head and limb elements project so slightly as to afford no real grip to the child and so cannot be injured or torn off. They do, however, bear sufficient resemblance to amuse and entertain.

In playing with the doll the child is required to exercise its grasping power in gripping the ring and additional exercise results from slipping the ring over the arm and from rolling the ring about in the manner of a hoop, the head and limb projections being so slight as to even allow of this latter use of the doll.

What is claimed is:

1. A doll comprising a ring having an opening therein of a size to pass on an infant's arm and having a conical head projection at one edge, hand projections at opposite sides of said head projection and feet projections below the hand projections.

2. A doll comprising a ring having an opening therein of a size to pass on an infant's arm and having a conical head projection at one edge, hand projections at opposite sides of said head projection and feet projections below the hand projections, said head and limb projections being of less extent than the width of the ring.

3. A doll comprising a complete ring substantially circular in cross section of a size to be grasped in an infant's hand and having an opening therethrough of a size to pass an infant's arm, said ring being self-sustained but flexible and having appropriately positioned but slightly projecting head and limb elements.

4. A doll comprising a ring-like member formed of a perimetric body, the cross sectional size of the body being such as to be readily grasped in an infant's hand, the opening in the ring being of a size to pass on an infant's arm, the ring having appropriately positioned head and limb elements, said elements projecting beyond said ring a distance not greater than the cross sectional size of the perimetric body.

In testimony whereof I affix my signature.

PHOEBE B. COOPER.
